ELECTRICAL ILLUMINATING DEVICE

Florian F. Manor, Oshkosh, Wis., assignor of one-third to A. B. Bechaud and one-third to A. T. Brenner, both of Fond du Lac, Wis.

Application September 9, 1932, Serial No. 632,359

2 Claims. (Cl. 177—329)

This invention relates to improvements in electrical illuminating devices and more particularly to devices for marking airway obstructions and for illuminating airway routes.

5 High tension lines for transmitting electric current are quite often located adjacent air ports and as a result these lines present quite a hazard to a plane which is landing or taking off after dark. The proper marking of these obstructions 10 by means of lights has presented a difficult problem in view of the fact that an ordinary electrical connection cannot be made with the lines because of the high voltage carried thereby. While it is, of course, possible to transmit current of proper 15 voltage from some removed points to lights arranged adjacent the high tension lines, this usually entails too great an expense to be practical.

It is one of the objects of the present invention to provide an electrical illuminating device which 20 is relatively inexpensive in construction, which can be quickly applied directly to a high tension line, and which is arranged to utilize the high voltage current supplied thereby.

A more specific object of the invention is to 25 provide an electrical illuminating device embodying a pair of electrodes for receiving current in which one of said electrodes is directly connected to one conductor of a high voltage line and in which the other electrode is positioned in spaced 30 relation from another conductor so as to induce current therefrom.

A further object of the invention is to provide 35 an electrical illuminating device which is constructed in a novel manner for suspension from a conductor of a transmission line.

A further object of the invention is to provide 40 an electrical illuminating device as above described wherein the suspension means is constructed to permit swinging of the device so as to prevent damage by the wind.

A further object of the invention is to provide a 45 device of the class described wherein the illuminating means may comprise a luminescent, gas filled tube.

A further object of the invention is to provide 50 an electrical illuminating device which is suitable for use not only as an obstruction marker but also to illuminate air routes and thereby serve as a guide to night fliers.

With the above and other objects in view, the 55 invention consists of the improved electrical illuminating device, and its parts and combinations as set forth in the claims, and all equivalents thereof.

In the accompanying drawing illustrating one 60 complete embodiment of the preferred form of the invention in which the same reference numerals designate the same parts in all of the views:

Fig. 1 is a front elevational view of the device showing it in connection with a conductor, part

of the device being shown in section and only a fragment of the conductor being illustrated;

Fig. 2 is a sectional view taken on line 2—2 of Fig. 1;

Fig. 3 is an enlarged fragmentary detail view 5 showing the juncture point of the tubes as they appear in front elevation;

Fig. 4 is a front elevational view of a transmission line tower showing the illuminating devices 10 as suspended from one of the transmission conductors; and

Fig. 5 is a similar view on a slightly larger scale showing the adaptation to a different type of transmission line.

Electrical transmission lines usually extend 15 from a point where electricity is generated to some removed point where sufficient energy for generating electricity is not present or where the generation of electricity would involve too great an expense.

These transmission lines usually carry 20 a plurality of conductors and they are generally arranged so that there are three sets of conductors spaced one above the other. Certain types

of transmission lines also include an upper 25 grounded conductor and lower conductors carrying the current. These transmission lines frequently extend for a great many miles across portions of the country and often times carry electricity over mountains or other natural obstructions.

In view of the great number of these 30 transmission lines which are in use throughout the country at the present time it happens that many air ports are located relatively near to one or

more of these obstructions.

The illuminating device of the present invention may be effectively utilized on those portions 35 of the transmission lines which are too near to an airport, for the sole purpose of pointing out the obstructions to the aviator or they may be suspended at intervals along the transmission lines as said lines extend across portions of the country where the transmission lines are in line with an air route.

By this means the air route 40 may be marked out in an inexpensive manner. Furthermore, where the transmission lines extend over mountains or hills the use of these devices on the portions of the lines extending

thereover is a great aid to a flier as it enables him to ascertain the nature of the landscape 45 and enables him to control his plane accordingly to avoid accidents.

Referring more particularly to the drawing, the numeral 8 designates an upper conductor of the transmission line which may be supported by 50 a tower 9 or by a pole 9' of the type shown in Fig. 5. This upper wire may be either one of the wires carrying high voltage current or may

be a grounded wire. Spaced below the wire 8 is 55 a second wire 10 which extends parallel thereto.

60

At the point on the wire 8 where it is desired to suspend one of the improved illuminating devices the said wire is preferably wrapped spirally with a metallic band 11. A clamping member 12 comprises a pair of complementary sections each having complementary semi-cylindrical upper grooves 13 and lower grooves 14. Nuts and bolts 15 may be utilized to cause clamping of the member 12 around the spiral wrapped portion of the conductor, the said conductor being received in the grooves 13 of the clamping member. A supporting tube, preferably of glass, has a U-shaped upper portion 16, which is supported in the lower grooves 14 of the clamping member. The clamping member is so constructed that while it will rigidly clamp the conductor, there will be a rather loose connection with the upper portion 16 so as to permit a certain amount of swinging movement of said supporting tube. The main portion of the supporting tube, indicated by the numeral 17, extends downwardly for a substantial distance and is disposed substantially midway between the arms of the U-shaped portion 16, the said supporting tube portion 17 being connected by an angular section 18 with one of the arms of the U-shaped part. The other arm of said U-shaped part is suitably secured as at 19 by means of tape or in any other manner to a portion of the luminescent tube to support the latter.

The said luminescent tube has an enlarged portion 20 disposed substantially in alignment with the supporting tube portion 17 and said enlarged portion joins with a narrowed portion 21 which extends away from the central supporting tube in one direction and which then is bent to provide a section 22 extending back toward the supporting tube portion 17 crossing the latter beneath the tube section 21 to form a section 23 extending away from the central support 17 in the other direction. Said section of the luminescent tube 23 is then suitably bent to provide a section 24 which extends back toward the central supporting tube beneath the sections 21 and 22 and then downwardly adjacent the supporting section 17 as at 25. The formation shown resembles an arrow having a depending tail portion.

The upper enlarged end portion 20 of the luminescent tube is provided with the usual electrode 26 which is connected by means of a section of wire 27 directly with the clamp 12 which makes rigid connection with the high voltage line conductor 8, and the lower end of the luminescent tube is formed with another electrode 28 having a wire 29 connected thereto, the said wire extending exteriorly of the tube and being coiled around a lower portion thereof as at 30. The said coil is preferably insulated by means of tape or the like 31.

At the juncture of the various crossing tube sections said sections are suitably bound together by means of tape 32 or the like. In addition the portion of the U-shaped tube part 16 which extends through the clamping member may be taped as at 16' to provide insulation and to prevent too much freedom for swinging movement.

The luminescent tube is constructed of glass in the usual manner and is the type containing suitable gases such as neon which are rendered

luminescent when current is passed through the tube.

With the device suspended as shown and with the upper electrode 26 electrically connected with the conductor 8, and the lower electrode 28 connected with the coil 30, there will be a leakance to the earth or to adjacent conductors which are at a potential different from that of the potential of the conductor to which the upper electrode is attached, thereby permitting an electrical discharge to take place through the tube due to such difference in potential.

In order to install the devices it is necessary to shut off the flow of current through the power lines temporarily. The installation, however, due to the simple means of support can be quickly accomplished. When the power is again turned on the tubes will be rendered luminescent due to the direct connection of one electrode with one conductor and to the induction of current to the other electrode from another conductor. It has been found that the current consumption of these devices is practically negligible when thus used.

It is, of course, obvious that the luminescent tube may be shaped in other ways from that shown, that is to form an outline other than that of an arrow. It is also to be understood that various other changes and modifications may be made without departing from the spirit of the invention and all of such changes are contemplated as may come within the scope of the claims.

What I claim is:

1. An illuminating device for high tension lines having conductors comprising an electrical illuminating tube having upper and lower terminals, a support to which said tube is secured, a clamp formed by a pair of complementary sections each having a pair of clamping grooves therein, means for drawing said sections together to rigidly secure a portion of one of the conductors of the high tension line in one set of grooves and to loosely engage the tube support in the other set of grooves, and means for electrically connecting the terminal of said tube to said upper conductor of the high tension line, said loose engagement of the clamp with the tube support providing for swinging movement of the tube to prevent breakage by the wind.

2. An illuminating device for high tension lines having conductors comprising a supporting structure having a U-shaped connecting part and having an elongated part extending from one of the arms of said U-shaped part, means for detachably securing said U-shaped part to one of the conductors, an electrical illuminating tube having a pair of spaced terminals and having an elongated extension part carrying one of said terminals and having a laterally extending part, means for securing said tube to the supporting structure with the elongated extension part of the tube adjacent to and braced by the elongated part of the supporting structure, the other arm of the U-shaped part of the supporting structure being rigidly secured to the laterally extending part of the illuminating tube to form a braced structure, and means for electrically connecting one of the terminals of the tube with one of said conductors.

FLORIAN F. MANOR.
